UNITED STATES PATENT OFFICE.

FRANCIS N. RICHARDSON, OF CLEVELAND, OHIO.

MATCH-SAFE.

No. 798,627.

Specification of Letters Patent.

Patented Sept. 5, 1905.

Application filed August 15, 1904. Serial No 220,807.

To all whom it may concern:

Be it known that I, FRANCIS N. RICHARDSON, a citizen of the United States of America, residing at Cleveland, in the county of Cuyahoga and State of Ohio, have invented certain new and useful Improvements in Match-Safes; and I hereby declare the following to be a full, clear, and exact description of the invention, such as will enable others skilled in the art to which it pertains to make and use the same.

This invention relates to improvements in pocket match-safes and attachments.

The object of this invention is to provide in a match-safe the following: A main compartment for matches, another compartment next adjacent the match-compartment and open at one side to accommodate the passage into and out of it of a holder or attachment employed in supporting or carrying a candle or means used to provide a flame which will burn longer than the flame of a burning match with the said attachment pivotally supported from the body portion of the match-safe, and a hinged cover for closing both compartments at the upper end of the match-safe, and thereby covering the upper end of the aforesaid attachment, with the latter and the aforesaid hinged cover arranged with their axes at a right angle to each other.

With these objects in view this invention consists in certain features of construction and combinations of parts hereinafter described, and pointed out in the claims.

In the accompanying drawings, Figure 1 is a top plan of an open match-safe embodying my invention. Fig. 2 is a side elevation of a closed match-safe embodying my invention. Fig. 3 is a view in perspective of the match-safe, showing the cover of the safe open and the attachment swung out of the recess or compartment occupied by the said attachment when the safe is closed. Fig. 4 is a vertical section on line 4-4, Fig. 3, looking outwardly.

Referring to the drawings, A indicates the body portion of my improved safe, which is provided with a compartment 10 for holding matches *m* and a compartment-forming recess 12 next adjacent and exteriorly of the match-compartment. The compartment 12 extends from the upper end to the lower end of the match-safe and has a bottom 13. The compartment 12 is arranged between the sides of the body portion of the match-safe.

A light-furnishing or flame-furnishing attachment is provided and comprises, preferably, a vertically-arranged cylindrical tube B, which is rigid with a leaf *b*, hinged or pivoted vertically, as at *b'*, to the forward side and exteriorly of the body portion of the match-safe and arranged to swing into or out of the compartment 12. The compartment 12 is therefore open at the forward side of the body portion of the match-safe. The inner side wall of the compartment 12 forms one of the narrower walls of the match-compartment 10.

The flame - furnishing attachment comprises, preferably, a tubular cylindrical slide D, snugly fitting interiorly of the slideway-forming tube B and slideable up and down the said tube. The slide D forms a socket for a candle C, which is forced or fitted at its lower end into the said socket. The slide D is provided at the inner side of the tube B with a lug or projection *d*, which extends through a lateral slot 15, formed in and extending longitudinally of the tube B. The member *d* of the socket D forms means by which the said socket may be taken hold of or engaged in actuating the same vertically as required to elevate the candle C upwardly out of the tube B, as shown in dotted lines, Fig. 4.

In the normal position of the parts the socket D, with the candle C, is in its lower position within the lower portion of the tube B, and the latter engages the compartment 12 of the match-safe.

The tube B is somewhat larger diametrically than the width of the side opening of the compartment 12, and the forward portion of the outer side wall of the said compartment is loose at its lower end from the bottom 13, as at 14, and forms a spring *a*, yieldable laterally and outwardly to accommodate the passage of the tube B into and out of the compartment 12, which spring acts to retain the said tube in the said compartment when the latter is occupied by the tube.

The match-safe is provided with a cover G for closing the upper ends of the compartments 10 and 12 and for covering the upper end of the flame-furnishing attachment. The cover G is hinged or pivoted horizontally, as at *g*, to the rear side of the body portion of the match-safe.

It will be observed also that my improved match-safe when its flame-furnishing attachment is swung out of the recess 12 will readily

stand upright when placed upon a table and that the cover when closed merely rests upon the upper end of the body portion of the match-safe and does not interfere with the withdrawal of the flame-furnishing attachment from the recess 12, and hence the use of the said attachment does not require the leaving of the cover in an open position, and the cover is preferably kept closed during the operation of the flame-furnishing attachment, so that there is no liability of an accidental ignition of matches from a flame issuing from the candle of the said attachment.

What I claim is—

- 15 1. A match-safe comprising a body portion having a match-compartment and another compartment arranged exteriorly of the match-compartment, with the second-mentioned compartment provided, at one side, with an opening extending from the upper extremity to the lower end of the body portion of the match-safe, and an attachment comprising a tubular member somewhat larger diametrically than the width of
- 20 25 the aforesaid opening and pivotally supported from the body portion and arranged to swing out of or into the second-mentioned compartment through the aforesaid opening, and the forward portion of the outer side wall of the second-mentioned compartment being loose at its lower end from the bottom of the match-safe, as at 14, so as to form a spring which is yieldable laterally and outwardly to accommodate the passage of the
- 30 35 aforesaid tubular member into and out of

the second-mentioned compartment, which spring acts to retain the said tubular member in the said compartment when the latter is occupied by the said tubular member.

2. A pocket match-safe comprising the following:—a main or match compartment extending from the upper extremity to the lower end of the body portion of the match-safe; a smaller compartment next adjacent the match-compartment and extending from the upper extremity to the lower end of the body portion of the match-safe and provided, at one side, with an opening extending from end to end of the compartment; a holder or attachment employed in supporting or carrying the candle or flame-furnishing means and pivotally supported from the body portion of the match-safe and arranged to swing out of and into the smaller compartment, and a cover for closing both compartments at the upper end of the match-safe and hinged to the body portion of the match-safe at the opposite side of the smaller compartment, and the said cover and the aforesaid attachment being arranged with their axis at a right angle to each other.

In testimony whereof I sign the foregoing specification, in the presence of two witnesses, this 11th day of August, 1904, at Cleveland, Ohio.

FRANCIS N. RICHARDSON.
